[57] CLAIM

The ornamental design for a safety bumper for guiding the visually impaired, as shown and described.

DESCRIPTION

FIG. 1 is a front elevation view of a safety bumper for guiding the visually impaired showing our new design; FIG. 2 is a right-side elevation view thereof, the left-side elevation being a mirror image of FIG. 2; FIG. 3 is a rear elevation view thereof; and, FIG. 4 is a bottom plan view thereof, the top plan being an inverted mirror image of FIG. 4.
